TRUSS

Edward Mantel, Harvel, Ill.

Application June 22, 1950, Serial No. 169,562

5 Claims. (Cl. 128—117)

1

This invention relates to trusses for the care of hernias, and has particular reference to an improved truss pad and novel means for attaching the pad to a truss belt.

An object of the invention is to provide a simple, durable and efficient truss pad of the type adapted for use in cases where the intestinal protrusion through a rupture of the muscles of the abdominal wall is of a relatively small area.

More specifically, an object of the invention is to provide a novel truss pad of the type having a regional face adapted to apply different pressures to local areas, respectively, of the abdomen, or to the immediate area of the rupture and to the adjacent surrounding area, whereby to return the protruding intestine to its normal portion and to support the abdominal muscles around the rupture in order to resist recurrence of the protrusion. In such cases, a firm holding pressure is applied directly over the area of the rupture, and a much lighter pressure is applied to the surrounding area to minimize tension on the skin and the attending discomfort.

Another object is to provide novel means for attaching the pad to a truss belt and for adjusting the pad relative thereto so as to vary the pressures applied to the abdomen.

In the accompanying drawings illustrating an embodiment of the invention:

Figure 1 is a fragmentary front elevational view showing the present pad attached to an end of a spring truss belt in accordance with the present invention;

Figure 2 is an enlarged section taken on the line 2—2 of Figure 1, with the pad partly broken away;

Figures 3 and 4 are sections taken respectively on the lines 3—3 and 4—4 of Figure 2;

Figure 5 is a side elevational view of the pad;

Figure 6 is a bottom plan view thereof;

Figure 7 is an enlarged section taken on the line 7—7 of Figure 6; and,

Figures 8 and 9 are elevational views of the local pressure applicator and main body member of the pad, respectively.

Referring in detail to the drawings, the present pad comprises a main body member 5, and a local pressure applicator 6, molded of sponge rubber or similar highly resilient material. The member 5 is of substantially hemispherical form, is provided with a flat base surface 7, and is formed in its crown or top portion with a central recess 8 of slightly greater than hemispherical shape. The applicator 6 is of substantially spherical form and has slightly more than one

2

half thereof snugly fitted and cemented in the recess 8, the remaining minor portion of said applicator protruding from the crown of the member 5. Thus, the applicator is forced into the recess 8 by causing the portion of member 5 about the top of recess 8 to expand until the equator of member 6 passes into said recess, whereupon said portion of member 5 contracts against the applicator 6 outwardly of its equator to aid in holding the applicator in said recess. The shape of the protruding portion of applicator 6 is such as to apply a firm holding pressure over the area of the rupture, and to apply a lighter pressure to the adjacent surrounding area, supplemented by the adjacent crown surface portion of the member 5.

In Figures 1 to 4 inclusive, the pad is shown as secured to a carrier 9, detachably and adjustably connected to one end of a plate 10, which is secured at its other end to an end of a spring truss belt 11. The carrier 9 comprises a flat plate 12 disposed against the base surface 7 of the pad member 5 and having angular marginal prongs 13 driven into the base portion of said pad member 5 to secure the pad to the carrier. Screws or bolts 14 are passed through openings of the belt plate 10 and carrier plate 12 and screwed into base sockets 15 of the pad member 5 to secure the carrier to the belt plate and aid in securing the pad to the carrier. The screws or bolts 14 may be such as to cut their own threads in the walls of the sockets 15. By loosening the screws or bolts 14, one or more shim plates 16 may be interposed between the belt plate 10 and the carrier plate 12 to adjust the distance at which the pad protrudes laterally from the belt plate and thereby vary the pressure applied to the abdomen by said pad. Each shim plate is provided with a diametric slot 17 to provide clearance for the screws or bolts 14 so that the shim plates may be inserted or removed by loosening or without completely removing said screws or bolts. A spacer plate 18 may be placed between the carrier plate 12 and the adjacent shim plate 16, said spacer plate having elongated slots 19 to receive the screws or bolts 14 and permit ready centering of said spacer plate. A soft flexible washer 20 may be used between the belt plate 10 and the adjacent shim plate.

From the foregoing description, the nature and advantages of the invention will be apparent. Minor changes may be made in the details of construction without departing from the spirit of the invention as claimed.

Having thus described the invention, what is claimed as new is:

1. In a truss, a pad comprising a main body member and a local pressure applicator composed of inherently resilient material, said body member being of substantially hemispherical solid form with a widest portion forming a flat base surface and, said member having a central concave recess of slightly greater than hemispherical shape in the crown portion thereof, said pressure applicator being of substantially spherical form and having slightly more than one half thereof snugly fitted and seated in said recess of the body member, the remaining minor portion of said pressure applicator protruding from said recess beyond the crown surface of the body member, the portion of the body member at the top of said recess gripping the pressure applicator outwardly of its equator to aid in holding said applicator in the recess, said crown portion having a pressure applying surface supplementing the minor portion of said pressure applicator in applying pressure.

2. In a truss, a resilient pad having a flat base surface, a carrier embodying a flat plate disposed against said base surface of the pad and having angular marginal spurs grouped around and driven into the sides of said pad adjacent said base surface.

3. In a truss, a resilient pad having a flat base surface, a carrier embodying a flat plate disposed against said base surface of the pad and having angular marginal spurs grouped around and driven into the sides of said pad adjacent said base surface, an end belt plate, and screws passing through said belt and carrier plates and screwed directly into the pad to secure the parts together.

4. In a truss, a resilient pad having a flat base surface, a carrier embodying a flat plate disposed against said base surface of the pad and having angular marginal spurs driven into the sides of said pad adjacent said base surface, an end belt

plate, screws passing through said belt plate and carrier plate and screwed into the pad to secure the parts together, and a removable shim plate interposed between the belt and carrier plates and slotted to clear the screws to permit insertion and removal of said shim plate upon merely loosening the screws.

5. In a truss, a flat carrier plate, a pad secured to said carrier plate, a belt plate, and means to connect the carrier plate to the belt plate and to adjust the pad and the carrier plate laterally relative to said belt plate so as to adjust the distance at which the pad protrudes from said belt plate and thereby vary the pressure applied to the abdomen by said pad, said means comprising screws passing through said carrier and belt plates, and a plurality of plates removably clamped between said carrier and belt plates by said screws and including a resilient washer plate, a spacer plate and a shim plate between said washer plate and spacer plates, said shim plate having a slot open at one end and having the screws passing therethrough to permit removal of said shim plate upon merely loosening said screws.

EDWARD MANTEL.
